TWIN LENS REFLEX CAMERA

Darrell R. Shipley, P.O. Box 2037,
Clarksville, Tenn. 37040

Filed May 14, 1968, Ser. No. 11,914

Term of patent 14 years

Int. Cl. D16—01

U.S. Cl. D61—1

Fig. 1

Fig. 2

Fig. 3

Fig. 4

Fig. 5

Fig. 6

Fig. 7

Fig. 8

FIGURE 1 is a side elevational view of the twin lens reflex camera as seen from the right side thereof and with a first form of removable back supported from the rear of the camera;

FIGURE 2 is a front elevational view of the embodiment of FIGURE 1 as seen from the right side thereof;

FIGURE 3 is a top plan view of the camera;

FIGURE 4 is a side elevational view of the left side of the camera;

FIGURE 5 is a bottom plan view of the camera;

FIGURE 6 is a rear elevational view of the camera; and

FIGURES 7 and 8 are rear elevational views of the camera with two different forms of removable backs secured thereto.

I claim:

The ornamental design for a twin lens reflex camera, as shown and described.
